UNITED STATES PATENT OFFICE.

AARON McGREGOR, OF SPRINGVILLE, MISSISSIPPI.

COTTON-CHOPPING MACHINE.

Application filed December 15, 1926. Serial No. 155,006.

This invention relates to cotton choppers, and has for one of its objects to provide a machine of this character which shall include an arm mounted for reciprocation transversely of the machine, blades carried by the arm and adapted to cut stands of cotton during the movement of the arm from and its return to its initial position, means for actuating the arm, and means by which the initial position of the arm may be easily and quickly adjusted to and secured in the required position with respect to the longitudinal center of the machine.

A further object of the invention is to provide a machine of the character stated which shall include means by which the arm may be easily and quickly adjusted vertically with respect to the machine and secured in adjusted position so as to position the blades at the required distance from the ground.

A further object of the invention is to provide a machine of the character set forth wherein the actuating means shall be adjustable to permit the length of the stroke of the arm and blades to be varied as conditions require.

A still further object of the invention is to provide a machine of the character set forth wherein the blades shall be connected to the arm in a manner to permit them to yield laterally on coming in contact with a stump or rock so as to prevent them from being broken or detached from the arm.

With the foregoing and other objects in view, the nature of which will become apparent as the description proceeds, the invention consists of a novel construction, combination and arrangement of parts hereinafter fully described and claimed, and illustrated in the accompanying drawings, wherein:

Figure 1 is a top plan view of a cotton chopping machine constructed in accordance with my invention,

Figure 2 is a sectional view taken on a vertical plane extending longitudinally and centrally through the machine,

Figure 3 is a sectional view taken on a horizontal plane extending longitudinally through the means for adjusting the blade carrying arm with respect to the longitudinal center of the machine.

Figure 4 is a sectional view taken on the vertical planes indicated by the line 4—4 of Figure 3.

Figure 5 is a sectional view taken on a horizontal plane extending longitudinally through the means for actuating the blade carrying arm,

Figure 6 is a sectional view taken on the vertical plane indicated by the line 6—6 of Figure 1,

Figure 7 is a sectional view taken on the vertical plane indicated by the line 7—7 of Figure 6,

Figure 8 is a sectional view taken on the vertical plane indicated by the line 8—8 of Figure 6,

Figure 9 is a sectional view taken on the horizontal plane indicated by the line 9—9 of Fig. 8,

Figure 10 is a sectional view taken on the horizontal plane indicated by the line 10—10 of Figure 7, and

Figure 11 is a sectional view taken on the vertical plane indicated by the line 11—11 of Figure 1.

Referring in detail to the drawings, in the several views of which like reference characters denote like parts, 1 designates the ground wheels, 2 the axle and 3 the main frame of the machine. The wheels 1 are free of connection with the axle 2 while rotating rearwardly, and are connected to the axle while rotating forwardly by ratchet wheels 4 and pawls 5 of which the former are fixed to the axle and the latter to the wheels. The frame 3 is provided with bearings 6 for the axle 2, and is equipped with a pole 7, doubletree 8, singletrees 9, and a breast yoke, not shown. The ends of the doubletree 8 are connected to the frame 3 by chains 10. A foot board or platform 11, upon which a seat 12 is mounted, is secured to the downwardly offset rear end portion of the frame 3.

A yoke or hanger 13, which is vertically disposed and extends transversely of the frame 3, is mounted for vertical adjustment at the front end of the frame in bearings 14, and is provided with horizontally disposed guide rails or tracks 15. Standards 16 and 16^a are secured at their lower ends to the

frame 3 between the axle 2 and platform 11, and the standard 16^a is provided at its upper end with a rearwardly extending notched sector 17. A lever 18 is fixed at one end to and extends forwardly from a shaft 19 which is journaled in the standards 16 and 16^a adjacent their upper ends. The front end of the lever 18 is connected to the yoke or hanger 13 by a flexible member 20. A lever 21 is fixed at one end to and extends rearwardly from the shaft 19, and is provided at its rear end with a handle 22 which is located adjacent the seat 12. The lever 18, shaft 19 and lever 21 provide means by which the operator may easily and quickly adjust the yoke or hanger 13 upwardly or downwardly with respect to the frame 3. The yoke or hanger 13 is secured in adjusted position by a spring pressed dog 23 which is carried by the lever 21 and engages the notched sector 17. The dog 23 is under the control of a finger lever 24 which is carried by the lever 21 adjacent the handle 22 and connected to the dog by a rod 25.

An arm 26 is connected at its upper end to the yoke or hanger 13 for reciprocation with respect thereto in a plane extending transversely of the machine. The blades 27 are adapted to cut stands of cotton during the movement of the arm 26 from and its return to its initial position. The arm 26 is connected to the yoke or hanger 13 by a bolt 28 which is secured to the arm and a grooved roller 29 which is journaled on the bolt and supported by the guide rails or tracks 15 of the hanger. As the arm 26 is connected to the yoke or hanger 13 it may be vertically adjusted to support the blades 27 at the required distance from the ground. To permit the arm 26 to be adjusted vertically with respect to the yoke or hanger 13, it is provided with a vertical row of bolt receiving screw threaded sockets 26^a.

The blades 27, which are located at opposite sides of the arm 26, are carried by the head 30 of a stem 31 which is journaled in the arm for movement about a vertical axis. The arm 26 is provided with a socket 32 for the reception of the stem 31 and with a recess 33 for the reception of a lug 34 on a bar 35. The recess 33 intersects the socket 32 and opens out through the rear side of the arm 26. Lugs 36 are fixed to the stem 31, and are positioned in the recess 33 in contact with the lug 34. A bar 37 is fixed to the front side of the arm 26, and together with the bar 35 is horizontally disposed and extends in opposite directions beyond the arm. The bar 35 is supported for movement toward and from the arm 26 by bolts 38 fixed to the bar 37, and is constantly urged in the direction of the arm by springs 39 carried by the bolts. The blades 27 are thus yieldingly supported in normal position with respect to the arm 26, and due

thereto will yield laterally on coming in contact with a stump or stone, with the result that they will not be broken or detached as the result of such contact.

A carriage 40 is mounted for reciprocation transversely of the machine upon a guide rail or track 41 which is carried by the frame 3. It is equipped with grooved rollers 42 which contact with the upper and lower sides of the guide rail or track 41, and is provided with a vertical groove 43 for the reception of a wrist pin 44 carried by a disk 45. The disk 45 is provided with a radial series of screw threaded sockets 46 to permit the wrist pin 44 to be adjusted thereon with respect to its axis. The arm 26 is connected to the carriage 40 by guides 47 for movement therewith and for vertical adjustment with respect thereto, through the medium of the yoke or hanger 13. The disk 45 is fixed to a shaft 48 which is journaled in a bearing 49 supported for adjustment transversely of the machine. A guide rail or track 50 supports the bearing 49 and is carried by the frame 3. The rotation of the disk 45 reciprocates the carriage 40 and with it the arm 26 transversely of the machine, and the movement of the carriage and arm may be varied to increase or decrease the stroke of the blades 27 by adjusting the wrist pin 44 with respect to the axis of the disk 45.

A power shaft 51 is journaled on the frame 3, and is driven from the axle 2 by a chain 52 which passes about sprocket wheels 53 and 54 fixed to the shaft and axle, respectively. A housing 55 is provided for the chain 52 and sprocket wheels 53 and 54.

A gear wheel 56 is slidably fixed to the shaft 51, and is provided with two rows of gear teeth 57 and 58 with one of which meshes a pinion 59 fixed to a transmission shaft 60. The shaft 60 is connected to the shaft 48 to effect the rotation of the disk 45 while the machine is in forward motion. The shaft 60 is sectional, and the sections 61, 62 and 63 thereof are connected by universal joints 64 so as to permit the bearing 49 to be adjusted when conditions require the changing of the initial position of the arm 26 with respect to the longitudinal center of the machine. The shaft section 62 consists of telescopically associated parts 62^a and 62^b to permit the effective length of the shaft 60 to increase or decrease during the adjustment of the bearing 49 and to permit the endwise adjustment of the shaft section 61 so as to position its pinion 59 in engagement with the teeth 57 or teeth 58 of the gear wheel 56 so as to vary the rate of rotation of the shaft 60 and consequently the stroke of the blades 27. The shaft section 61 is rotatably and slidably mounted in a bearing 65 which is carried by the frame 3. A housing 66 for the gear wheel 56 and the

pinion 59 is secured to the bearing 65. The gear wheel 56 is held in normal position, in which position it meshes with the pinion 59, by a spring 67, and the movement of the gear wheel under the influence of the spring is limited by a shoulder 68 on the shaft 51. When it is desired to move the pinion 59 from engagement with the teeth 57 into engagement with the teeth 58 or from engagement with the teeth 58 into engagement with the teeth 57, so as to vary the stroke of the blades 27, the gear wheel 56 is first moved laterally out of engagement with the pinion 59, the shaft 61 is then adjusted to position the pinion 59 in alignment with the desired teeth and locked in adjusted position, and the gear wheel is thence released to permit it to be moved into engagement with the pinion by the spring 67. The gear wheel 56 is under the control of a lever 69 pivoted as at 70 to the frame 3. A vertical shaft 71 is journaled in the housing 66, for rotation about a vertical axis and is provided at its lower end with a forwardly extending forked crank 72 which is engaged in a groove in the hub 73 of the gear wheel 56. The shaft 71 is provided at its upper end with a laterally extending crank 74 to which the lever 69 is connected by a link 75. The lever 69 is held against casual movement by a spring pressed dog 76 which is carried thereby and engages a notched sector 77 fixed to the frame 3. The dog 76 is under the control of a finger lever 78 which is pivoted to the lever 69 and connected to the dog by a rod 79. As the shaft 71 is mounted for rotation about a vertical axis, and as its cranks 72 and 74 are arranged in right angularly related planes, it will when turned as the result of the forward rocking of the lever 69 swing its crank 72 in a direction to move the gear 56 out of engagement with the pinion 59 against the tension of the spring 67. When the lever 69 is rocked rearwardly, the shaft 71 will be turned in a direction to swing its crank 72 in the opposite direction and thus permit the spring 67 to move the gear 56 into engagement with the pinion 59. The shaft section 61 is adapted to be moved in an endwise direction to effect the engagement of the pinion 59 with either the teeth 57 or teeth 58 of the gear wheel 56 through the medium of a lever 80 which is pivoted as at 81 to the bearing 65. A collar 82 fixed to the shaft section 61, a casing 83 surrounding and having a rotatable connection with the collar and shaft section, and a link 84 connected as at 85 to the lever 80 and having a forked end connected as at 86 to the casing 83, connect the lever 80 to the shaft 61. The lever 80 is secured against casual movement by a spring pressed dog 87 which is carried thereby and engages a notched sector 88 fixed to the bearing 65. The dog 87 is under the control of a

finger lever 89 carried by the lever 80 and connected to the dog by a rod 90.

The means for adjusting the carriage 40 and securing it in adjusted position so as to vary the initial position of the arm 26 and blades 27 with respect to the longitudinal center of the machine, comprises a rack bar 91 connected as at 92 to the bearing 49 and slidably supported upon the guide rail or track 50 by guides 93. A pinion 94 meshing with the rack bar 91, is fixed to a shaft 95 journaled in a bearing 96 carried by the frame 3. A second pinion 97 is fixed to the shaft 95 and meshes with pinions 98 and 99. The pinion 98 is fixed to a shaft 100 and the pinion 99 to a shaft 101. The shaft 100 is journaled in the bearing 96 and in a bearing 102 loosely connected to the axle 2, and consists of sections connected by a universal joint 103. The shaft 101 is journaled in the bearing 96 and a bearing 104 loosely connected to the axle 2, and consists of sections connected by a universal joint 105. The bearings 102 and 104 are maintained in relatively spaced relation by a spring 106 mounted between them upon the axle 2. Gear wheels 107 and 108 are loose on the axle 2 and mesh with pinions 109 and 110 fixed to the shafts 100 and 101, respectively. Means for establishing a driving connection between the gears 107 and the axle 2 when it is desired to adjust the bearing 49 and the parts associated therewith to the left, is under the control of a pedal 111, and means for establishing a driving connection between the gear 109 and the axle 2 when it is desired to adjust the bearing and the parts associated therewith to the right, is under the control of a pedal 112. The adjustment of the bearing 49 varies the initial position of the arm 26 and the blades 27 with respect to the longitudinal center of the machine. The pedals 111 and 112 are pivoted to the platform 11 forwardly of the seat 12. These means are similar, and each comprises a drum 113 fixed to each of the gears 107 and 108, a disk 114 fixed to the axle 2, a split band 115 pivoted as at 115^a to the drum and normally out of contact with the annular wall thereof, a link 116 pivotally connected to the free ends of the band, and a disk 117 to which the link 116 is pivotally connected as at 116^a. The disks 117 are loose on the axle 2, and are adapted to be held against movement, to effect the expanding of the bands 115, and thus lock the gears 107 and 108 to the axle 2, by means of the pedals 111 and 112, split bands 118 mounted in their grooved peripheries, links 119 connected to the free ends of the bands, and rods 120 connected to the links and pedals. The bands 118 are normally out of contact with the disks 117, and when the pedals 111 and 112 are depressed, are contracted into engagement with the disks, with 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950 955

the result that the gears 107 and 108 will be rotated by the axle 2. It will thus be seen that when the pedal 111 is depressed, the initial position of the arm 26 and blades 27 will be shifted to the left, and that when the pedal 112 is depressed the initial position of the arm and blades will be shifted to the right. When the pedals 111 and 112 are under pressure, the driving connection between the axle 2 and gears 107 and 108 is broken, and the initial position of the arm 26 and blades 27 will remain fixed.

From the foregoing description, taken in connection with the accompanying drawings, the advantages of the construction and of the method of operation will be readily apparent to those skilled in the art to which the invention appertains. While I have described the principle of operation of the invention, together with the structure which I now consider to be the best embodiment thereof, I desire to have it understood that the structure shown is merely illustrative, and that such changes may be made when desired as are within the scope of the invention as claimed.

What is claimed is:—

1. A cotton chopping machine comprising a frame, an arm, blades carried by the arm, a carriage for supporting the arm and mounted on the frame for reciprocation transversely of the machine, means for actuating the carriage and mounted on the frame for adjustment transversely of the machine, and means for adjusting said first means and securing it in adjusted position.

2. A cotton chopping machine comprising a frame, an arm, blades carried by the arm, a carriage for supporting the arm and mounted on the frame for reciprocation transversely of the machine, means for actuating the carriage and mounted on the frame for adjustment transversely of the machine, and means for adjusting said first means transversely of the frame and securing it in adjusted position, said first means being also adjustable to permit the extent of the reciprocation of the carriage to be varied.

3. A cotton chopping machine comprising a frame, a carriage mounted on the frame for reciprocation transversely of the machine, an arm provided with blades, means securing the arm to the carriage for movement therewith and for vertical adjustment with respect thereto, means for actuating the carriage and mounted on the frame for adjustment transversely of the machine, means for adjusting the carriage actuating means and securing it in adjusted position, and means for adjusting the arm vertically with respect to the carriage.

4. A cotton chopping machine comprising a frame, a carriage mounted on the frame for reciprocation transversely of the machine, means for actuating the carriage, an arm

provided with blades, means securing the arm to the carriage for movement therewith and for adjustment vertically with respect thereto, a hanger, means mounting the hanger on the frame for vertical adjustment, means for adjusting the hanger, and means connected to the arm and associated with the hanger for movement with respect to the latter in a direction transversely of the machine.

5. A cotton chopping machine comprising a wheel supported frame, a bearing mounted on the frame for adjustment transversely with respect to the machine, means for adjusting the bearing, a shaft journaled in the bearing, means for rotating the shaft, a carriage supported by the frame for reciprocation transversely of the machine, means establishing an operative connection between the shaft and carriage, an arm associated with the carriage, and blades carried by the arm.

6. A cotton chopping machine comprising a wheel supported frame, a bearing mounted on the frame for adjustment transversely thereof, a rack bar connected to the bearing, a pinion meshing with the rack bar, means for turning the pinion in opposite directions for effecting the adjustment of the bearing, a shaft journaled in the bearing, means for rotating the shaft, a carriage mounted on the frame for movement transversely of the machine, means establishing an operative connection between the shaft and carriage, an arm associated with the carriage, and blades carried by the arm.

7. A cotton chopping machine comprising wheels, an axle, a frame, a bearing mounted on the frame for adjustment transversely of the machine, a rack bar connected to the bearing, a pinion meshing with the rack bar, gears loose on the axle, shafts engaged with the gears and connected to the pinion, means by which a driving connection may be established between either of the gears and the axle to effect the adjustment of the bearing, a shaft journaled in the bearing, a carriage mounted on the frame for movement transversely of the machine, means establishing an operative connection between the shaft and carriage, means for rotating the shaft, an arm associated with the carriage, and blades carried by the arm.

8. A cotton chopping machine comprising a wheel supported frame, an arm movably mounted on the frame, means for operating the arm, a stem rotatably carried by the arm, blades carried by the stem, means yieldingly holding the stem against rotation with respect to the arm, said means comprising lugs carried by the stem, a bar with which the lugs contact, means movably connecting the bar to the arm, and means urging the bar in the direction of the lugs.

9. A cotton chopping machine comprising

a wheel supported frame, an arm, means movably supporting the arm and mounted on the frame for reciprocation transversely of the machine, blades carried by the arm, a bearing adjustably mounted on the frame, means for adjusting the bearing, a shaft journaled in the bearing, means establishing

a driving connection between the shaft and said first means, a flexible and extensible transmission shaft connected to the first 10 named shaft, and driving means for the transmission shaft.

In testimony whereof I affix my signature.

AARON McGREGER.
